UNITED STATES PATENT OFFICE.

WILLIAM F. CREMEAN, OF WILKES-BARRE, PENNSYLVANIA.

BRAKE-HANGER.

1,304,662.

Specification of Letters Patent. Patented May 27, 1919.

Application filed September 16, 1918. Serial No. 254,244.

To all whom it may concern:

Be it known that I, WILLIAM F. CREMEAN, a citizen of the United States, residing at Wilkes-Barre, Pennsylvania, in the county of Luzerne and State of Pennsylvania, have invented certain new and useful Improvements in Brake-Hangers, of which the following is a specification.

My present invention relates to improvements in brake hangers and aims to provide a simple, economical, strong and durable construction which will avoid all danger of the brake beams dropping on the rails due to breakage of parts or working out of keys.

The invention includes the novel features of construction and arrangement and combination of parts hereinafter described and particularly defined by the appended claims, the invention being illustrated by the accompanying drawings, in which—

Figure 1 is a front elevation of a supporting lug and hanger embodying my invention, the brake-head and shoe being omitted.

Fig. 2 is a side elevation.

Figs. 3 and 4 are detail views illustrating the manner of inserting the hanger supports in the bracket.

Fig. 5 is a side elevation of one of the hanger supports.

Fig. 6 is a detached front view of the two hanger supports.

Fig. 7 is a section on line 7—7 of Fig. 5.

Fig. 8 is a section on line 8—8 of Fig. 5.

Fig. 8^a is a detail of the locking pin.

Fig. 9 is a section on line 9—9 of Fig. 1.

Figs. 10 and 11 are respectively a front view and side elevation of a modification.

Referring by reference characters to this drawing the numeral 12 designates a bracket designed to be secured in any suitable manner to the truck frame and provided with a pair of depending spaced lugs 12^a having transverse circular passages or recesses 12^b therethrough. 13 and 14 designate the hanger supporting members which are provided near their upper ends with lateral cylindrical projections 13^a and 14^a designed to fit in the passages or recesses 12^b, and

50 which are further provided in their lower parts with recesses 13^b and 14^b designed to receive the upper ends of the brake beam hanger 15 which is held therein by a pin 16

in the manner hereinafter more particularly described.

The hanger supports are made in the two parts, 13 and 14, to enable them to be applied to the brackets and locked in position with the studs or projections pivotally supported in the openings or recesses 12^b and 60 to this end the member 13 is made with a lateral cut away portion or channel 13^c which corresponds in width to the width of the upper end of the member 14. Thus after the member 13 has been inserted between 65 the legs 12^a and moved laterally until its stud or projection 13^a lies in the corresponding opening or recess or passage 12^b and said member is allowed to drop or rest in vertical position, the member 14 is held in 70 horizontal position or at right angles to member 13 and its upper end inserted in the transverse recess 13^c until the stud 14^a is in line with the corresponding recess or passage 12^b. Thereafter the member 14 is 75 moved laterally away from the member 13 until stud 14^a is entered in said recess or passage 12^b, when said member 14 is allowed to drop or is swung into a position parallel with the member 13 bringing the 80 upper end of member 14 out of line with the channel 13^c, thus holding the parts against any inward movement and automatically locking the studs in the recesses from which they cannot be removed without swinging 85 one member into a position at right angles to the other. As the members are held in alignment by the hanger iron and connecting pin it will be seen that accidental disconnection of the hanger supports is effectively prevented.

The brake shoe hanger is preferably of endless or integral form and comprises parallel bars 15^a and 15^b on each side of the brake head and hanger.

The bars 15^a and 15^b on each side are connected at their upper ends by an integral bend and the loops thus formed are inserted in the recesses 13^b and 14^b and are held therein by the locking pin 16 inserted in a 100 slot 16^b formed in hanger supports 13 and 14. This latter has at one end an offset portion or lug 16^a and when the hanger is inserted in the position shown in dotted lines in Fig. 4 and the pin inserted in slot 16^b 105 until the lug 16^a alines with recess 13^b the

55

turning of the hanger downward from the horizontal will bring the lug into the groove, locking the pin in position against accidental displacement.

- 5 The lower ends of hanger arms or bars 15^a are connected by transverse bars 15^c and 15^e, preferably integral with the hanger arms so that while I provide only a unitary hanger it is in effect a double hanger and therefore of maximum strength. The bottom ends or cross bars 15^c and 15^e are so made that a standard M. C. B. head can be used. The head is shown at 16^c, the brake shoe at 17 and the beam at 18, the full lines 15 showing the position of the parts with a worn brake shoe pressed against the wheel, and the dotted lines with an unworn shoe out of contact with the wheel.
- 20 The cross bars of the hanger arms are pivotally engaged in the recesses in the head as clearly shown in Fig. 2 and one of the hanger arms is provided with a lug 15^d designed to contact with the back of the head in case the shoe should back off.
- 25 To remove the beam the shoes at both ends are removed and the beam tilted toward the wheels so that the tops of the heads will point toward the wheels allowing the cross bar 15^c in the lower slot to be disengaged 30 when the heads can be lifted up and backed out of the hanger.

The lower cross bar 15^c is made of egg shape in cross section to engage the back of the shoe to keep the hanger in rigid connection with the head.

An important function of my invention is to prevent brake shoes from being unevenly worn and therefore scrapped before being completely used up. As the hanger is rigidly connected to the head it follows that the hanger is always in the same position relative to the head, and as the hanger supports swing on a short radius the weight of the brakes alone will insure a quick and complete release of the brakes.

Instead of using a bracket with spaced lugs, I may use a bracket with a single lug as shown at 12^x in Fig. 10. In this event the hanger supporting members 13^x and 14^x are shaped at their upper ends to lie against the outer faces of the lug 12^x and are provided with transverse holes to receive the holding pin 19. The member 13^x has a lug α adapted to engage a side of the head on the bolt 50 to prevent the latter from turning. The bolt having been passed through the member 13^x and then through the aperture in the lug and having been brought into a depending position the member 14^x is applied to the 55 projecting end of the bolt while in a horizontal position or at right angles to member 13^x, the key 20 having been first inserted through a transverse key receiving opening in the end of the bolt. The head of member 14^x has an annular channel 19^a to receive

the key and a passage 19^b through which the key passes into the channel when the member 14^x is at right angles to the member 13^x. In all other positions the bolt is locked in position by the key and the key retained in place by the wall of the annular groove or channel.

In the form shown in Figs. 10 and 11 the hangers are connected to the supports in the same manner as in the preceding form of the invention.

Having thus described my invention, what I claim is:—

1. In combination, a supporting bracket, a pair of hanger supports, means for pivotally connecting said supports to the bracket, said means operating to permit the members to be connected to the bracket when said members are at angles to each other and being automatically locked by the alinement of the members, and brake shoe hangers pivotally connected with said members.

2. In combination, a supporting bracket, a pair of hanger supports, means for pivotally connecting said supports to the bracket, said means operating to permit the members to be connected to the bracket when said members are at angles to each other and being automatically locked by the alinement of the members, and brake supporting hangers connected to the lower ends of said supports and normally holding them in alinement.

3. In combination, a supporting bracket, a pair of hanger supports, means for pivotally connecting said supports to the bracket, said means operating to permit the members to be connected to the bracket when said members are at angles to each other and being automatically locked by the alinement of the members, said supports having recesses in their lower ends, U-shaped hanger arms having their bent portions inserted in said recesses, a key passing through the supports and engaging said bends, and a brake shoe head supported from said hanger arms.

4. In combination, a supporting bracket, a pair of hanger supports, means for pivotally connecting said supports to the bracket, means operating to permit the members to be connected with the bracket when out of alinement and locking them thereto when alined, said members having recessed lower ends, U-shaped hangers, seated in said recesses, and a pin passing through said supports and engaging the bends of the hangers, said pin having a projection normally held by the hangers in one of the recesses to lock the key in position.

5. In combination, a supporting bracket, hanger supporting means pivotally connected with said bracket, two pairs of parallel hanger arms, integral cross bars connecting

125

130

the respective arms of the opposite pairs, the cross bars at the upper ends being pivotally connected with said hanger supporting means, and brake shoe heads supported by the lower cross bars.

5 6. In combination, a supporting bracket, hanger supporting means pivotally connected with said bracket, two pairs of parallel hanger arms, integral cross bars connecting the respective arms of the opposite pairs, the cross bars at the upper ends being pivotally connected with said hanger supporting means, a brake shoe head having recesses engaged by the lower cross bars.

10 15 7. In combination, a supporting bracket, hanger supporting means pivotally connected with said bracket, two pairs of parallel hanger arms, integral cross bars connecting the respective arms of the opposite pairs,

the cross bars at the upper ends being pivotally connected with said hanger supporting means, a brake shoe head having recesses engaged by the lower cross bars, and a lug on one of said arms for contact with the back of the shoe head.

20 25 8. In combination, a supporting lug having an aperture, a pair of hanger supports having corresponding apertures, a bolt passing through said apertures, one of said hanger supports having a part engaging the bolt head, a key in the other end of the bolt, the other hanger support having an annular flange to overlie the ends of the key, said flange having a cut away portion to permit insertion of the key when the hanger supports are out of alignment.

30 35 In testimony whereof I affix my signature.
WILLIAM F. CREMEAN.
